UNITED STATES PATENT OFFICE.

WALTER EVERETT MOLINS, OF LONDON, ENGLAND.

MACHINE FOR WRAPPING AND PACKING SMALL ARTICLES SUCH AS CIGARETTES.

Application filed June 13, 1921. Serial No. 477,202.

To all whom it may concern:

Be it known that I, WALTER EVERETT MOLINS, a citizen of the United States of America, residing in London, England, 5 have invented certain new and useful Improvements in Machines for Wrapping and Packing Small Articles Such as Cigarettes, of which the following is a specification.

This invention relates to improvements 10 in machines for wrapping and packing small articles such as cigarettes.

The particular object of the invention is to provide a machine adapted to work in co-operation with a cigarette conveying machine of the kind wherein bunches of cigarettes are continuously carried along to be packeted on an endless conveyor system such for example as is described in the specification of British Letters Patent No. 13957 of 15 1915. The invention however is also applicable for use with machines in which the bunches of cigarettes are intermittently fed.

According to the invention the wrapping machine is so arranged that the wrapping material is continuously fed from a reel or 20 the like, cut into desired lengths, applied to and folded or wrapped round each bunch of cigarettes on the conveyor system without affecting the continuous feed of the wrapping material or the movement of the bunches of cigarettes.

The wrapped bunches of cigarettes are then passed to the packeting portion of the machine. This portion of the machine comprises a magazine adapted to hold a series of superposed open mouthed packets, and an oscillating mouth-piece or funnel which is adapted to be moved into engagement with the mouth of the lowest packet and into 25 which the cigarettes or other articles are forced by the filling means. The filling means also operate to force the articles into the packet and to remove the filled packet, allowing the next packet on the magazine 30 to drop into the filling position. Means are provided for holding the packet being filled in position until the filling is complete, said means then yielding to allow the filled packet to pass away and returning automatically to hold the next packet in position.

To enable the invention to be fully understood it will now be described by reference to the accompanying drawings in which:

55 Fig. 1 is a plan view of the wrapping

portion of the machine constructed according to one form of the invention.

Fig. 1^a is a plan view of the machine bed a portion of the bed plate being removed to show the conveyor.

60 Fig. 2 is a front elevation thereof, the guides for the wrapping material and the folders being removed.

Fig. 3 is a sectional elevation on line 3—3 Fig. 1 shewing the feeding, guiding and 65 folding means for the wrapping material, and part of the packeting portion of the machine.

Fig. 4 is a plain view of the knife shewing the various positions it takes up during its 70 operation.

Fig. 5 is an end view of the knife in position A looking at Fig. 4 in the direction of the arrow A.

75 Figs. 6, 7 and 8 are side elevations shewing the progressive stages of the folding of the packet at the points a, b, c, Fig. 3 respectively and:

Fig. 9 is a side view of the completely 80 folded packets.

Fig. 10 is a sectional elevation of the packeting portion of the machine constructed according to the invention, the parts being in the position in which the cigarettes are about to enter the packets.

85 Fig. 11 is an elevation of the apparatus as seen from the right of Fig. 10 certain portions thereof being removed.

Fig. 12 is a view similar to Fig. 10 with the parts in the position in which the filled 90 packet is being ejected.

In the drawings a bunch of cigarettes 1 is shewn advancing on a bed plate 2 under the action of a pusher or carrier 3 mounted on a spindle 3^a, forming part of an endless 95 conveyor. The conveyor as shown in Fig. 1^a comprises side chains 80 one on each side of the machine bed 2 and below the same, the spindles 3^a carrying the pushers being mounted between the chains. The machine 100 bed 2 is provided with a slot 81 through which the connecting pieces 82 of the pushers 3 project so that the pushers slide on the bed plate. This conveyor and pushers are of known construction. It will be understood that the conveyor is continuously 105 driven and carries a series of bunches 1.

The wrapping mechanism is carried on a suitable framing 4 mounted on standards 5 arranged on a suitable part of the machine 110

frame and comprises a pair of feed rollers 6, 7 adapted to be rotated continuously to feed a strip of wrapping material 8 drawn from a supply reel (not shewn). The roller 7 is mounted in a carrier 9 pivoted at 10 to an arm 11 which in turn is pivoted at 12 to the frame. This arm 11 is held in working position by a tension spring 13 attached to a pin 14 slidable in a socket 15 in 10 the arm and to a pin 16 slidable in a fixed sleeve 17. By removing the pins 14 and 16 the roller 7 can be swung out of engagement with the roller 6 and may be held out of engagement by means of a sliding pin 18 carried in the frame, adapted to enter a hole 19 in the arm 11. The roller 6 is mounted on a spindle 20, having a bevel wheel 21 gearing with a bevel wheel 22 carried on a vertical spindle 23. The wheel 22 is driven by a bevel wheel 24 carried on a spindle 25 mounted in the sleeve 17 and adapted to be continuously driven by a wheel 26. This wheel 26 is the main drive wheel of the machine and may be either a gear wheel or a friction wheel, power being applied thereto by any suitable means not shown, such as a chain or belt.

The material 8 passes between the feed rollers 6, 7 through guides 27 (Fig. 3) into 30 a chute 28 and through a slot 29 in the bed plate (Figs. 1^a and 2) vertically across and below the path of the cigarettes 1.

The advancing ends of the cigarettes 1 meet the material 8 and carry it between 35 the folders contained in a box or casing 30. At the instant when the cigarettes thus meet the strip 8 the latter is severed at a point just below the guides 27 by a knife 31 actuated in the following manner. The 40 blade 31 (Figs. 2, 4 and 5) is mounted on a spindle 32 pivotally carried in a sleeve 33 which is clamped upon the spindle 23 by an arm 34 secured by a bolt 35, so that the sleeve is carried round as the spindle 23 rotates in the direction of the arrow Fig. 4. The spindle 32 has a coiled spring 36 on its lower end, one end of which is secured to the cap 37 screwed on the spindle, the other end being attached to the 45 sleeve 33. A fixed stop 38 is arranged in the path of the knife, and the latter has a thickened portion 39 adapted to meet the stop as shewn in the dotted position A Fig. 4.

50 As the spindle 23 continues to rotate the stop 38 pressing on the portion 39 detains the knife forcing it back until the portion 39 slips therefrom (position B Fig. 4). During this operation the spring 36 has 55 been compressed and when the knife leaves the stop, the spring exerts its force and throws the knife rapidly across the material 8, severing it so rapidly that there is no appreciable variation in the continuous feed 60 of the material (position C, Fig. 4). A

suitable limit stop 40 is provided on the arm 34 for the knife. The severed strip 8 is continuously advanced and is forced by the cigarettes into the casing 30, the first action being to form the strip into a U shaped 70 packet covering the top and bottom horizontal sides and the bottom of the bunch 1 as shewn in Fig. 3. The casing contains folders 41, 42 on each side thereof of any suitable construction which as the 75 packet passes through, fold the overlapping sides and turn in the bottom corners in the successive stages indicated in Figs. 6, 7 and 8 which are side elevations of the packet showing the progress of the folding operation at the points *a*, *b*, *c*, respectively of its travel through the folders Fig. 3. These folders, as has been said, are of known construction and form the material 8 about the cigarettes, which then pass out as a completely folded package 22' open at its mouth, as shown separately in Fig. 9. The finished packet is shewn in Fig. 9 and it will be seen that it is open at the mouth.

By means of the screw collars 5^a mounted 85 on the standards 5, the knife and the whole wrapping apparatus are adjustable in relation to the cigarettes so that the wrapping material may be located centrally with the cigarettes. It will be understood that any 90 suitable known folding arrangements may be employed for folding the wrapping material 8 after it has been placed around the cigarettes in a U shaped packet as indicated above.

In the apparatus hereinbefore described and illustrated the wrapping material is fed vertically into the path of the bunches of cigarettes, but obviously the apparatus could be modified to feed the said material 105 horizontally or at any desired angle into the path of the cigarettes, without departing from the spirit of the invention. For example the present apparatus could be so arranged that the material is fed horizontally, and the cigarettes vertically or at 110 any other suitable angle.

The folded packet 22' shewn in Fig. 9, then passes to the packeting portion of the machine illustrated in Figs. 10 to 12.

As shewn the packeting apparatus comprises a magazine 1' supported on the bed plate 2 which forms the bottom thereof. The magazine contains a series of superposed open mouthed packets 4' which may 120 be continuously or otherwise fed therein through the chute 5'. The packets are fed into the magazine with their open mouths towards the filling side 6', and openings 7' are provided at the bottoms of the sides 6' and 8'. An oscillating filling funnel 9' may 125 be introduced through the opening 7' in the side 6', the funnel thus entering the open mouth of the lowest packet. The funnel 9' is mounted on an arm 10', rigidly con- 130

nected to an arm 11' which is pivoted at 12' to a suitable portion of the frame, a spring 13' being provided which normally holds the funnel 9' clear of the front opening 7'. (See dotted line position Fig. 10).

The filling funnel is so formed that its opening at the smaller end is considerably smaller than the articles to be pushed therethrough, but can yield under pressure to 10 allow the articles to be forced through same. To this end the funnel may be formed of spring blades for example suitably mounted in any convenient manner. An adjustable stop 14' is provided for limiting the motion 15 of the funnel towards the magazine.

A pivoted tongue 15' is provided at the back 8' of the magazine adjacent the opening 7' therein; normally held in contact with the end of the lowest packet by a 20 roller 16' carried on a pivoted arm 17' under the action of a tension spring 18'.

A notch 19' is provided in the tongue 15' in which the roller 16' normally rests, the surface of the tongue around the notch being 25 arc shaped so that the roller can ride thereon when the tongue is pressed back from the magazine. It will be understood that the roller 16' operates to force the tongue 15' back into engagement with the 30 lowest packet in the magazine when a packet has been ejected.

This packeting portion of the machine is placed as indicated in Fig. 3, with the oscillating filling funnel 9' arranged in the 35 path of the wrapped packet 22' issuing from the casing 30. The operation of the apparatus is as follows:—Each wrapped bunch of cigarettes 22' on the conveyor issuing from the casing 30 passes along under 40 the action of its pusher 3 until it meets the wider end of the funnel 9'. The pusher 3 forces the bunch into the funnel, the spring blades or sides of the funnel being arranged to offer a greater resistance to the passage 45 of the cigarettes therethrough than the spring 13' which holds the funnel 9' away from the opening 7' in the magazine. Continued movement of the pusher 3 therefore carries the funnel 9' into the opening 50 7' and causes the smaller end of the funnel to enter the open mouth of the lowest packet. Further movement of the pusher 3 then overcomes the resistance of the funnel and causes the cigarettes to be pushed therethrough into the packet. When the cigarettes reach the bottom of the packet the 55 continued movement of the pusher 3 causes the packet to be ejected through the opening 7' in the back of the magazine the tongue 60 15' yielding as shewn in Fig. 12. When the packet is entirely ejected, the next packet in the magazine falls into position for filling, the tongue 15' returning to the position shewn in Fig. 10, and the funnel 9' 65 springing back clear of the magazine as

shewn in dotted lines Fig. 10, as will be readily understood. The next wrapped bunch 22' of cigarettes arrives and the operations are repeated.

The bottom of the funnel 9' is slotted or 70 grooved for the passage of the pushers 3, and the slot 81 is continued through the magazine when the invention is used with filling apparatus of the kind illustrated.

If however the filling member is of the 75 known reciprocating plunger type, the plunger will be withdrawn as soon as the packet has been pushed out of the magazine; thus allowing the tongue 15' to return to its original position and allowing the funnel 80 9' to be lifted clear of the opening 7', and also the fall of the next packet into the filling position in the magazine.

In the example hereinbefore described the oscillating mouthpiece or funnel is operated 85 by the movement of the cigarettes under the action of the filling means. Obviously, the mouthpiece or funnel could be operated in other ways, for instance, the filling means may operate thereon other than through the 90 cigarettes, or independent means may be provided for positively operating said mouthpiece or funnel.

Having thus particularly described and ascertained the nature of my said invention, 95 and the best means I know of carrying the same into practical effect, I claim:—

1. In a machine for packing cigarettes or other articles and in combination a conveyor for moving the articles to be packed, 100 a magazine adapted to receive a series of superposed packets with their open mouths arranged towards the articles moved by the conveyor, and an oscillating mouthpiece which receives the articles to be packed, 105 operated by the movement of said articles to insert same in the lowermost packet in the magazine automatically.

2. In a machine for packing cigarettes or other articles and in combination a conveyor for moving the articles to be packed, 110 a magazine adapted to receive a series of superposed packets with their open mouths arranged towards the articles moving on the conveyor, a funnel pivotally mounted adjacent the magazine with its smaller end towards said magazine and a spring normally holding said funnel clear of the filling side of the magazine, the articles moving on the conveyor being caused to enter the 115 wider end of the funnel said funnel being so shaped that sufficient resistance to the passage of the articles therethrough is obtained to cause the movement of the articles to force the smaller end of the funnel into the lowermost packet in the magazine and also to force the articles out of the funnel into the packet.

3. In a machine for packing cigarettes or other articles, and in combination, a con- 120

veyor for moving the articles to be packed, a magazine adapted to receive a series of superposed packets with their open mouths arranged towards the articles moving on the conveyor, a funnel formed of spring fingers pivotally mounted adjacent the magazine with its smaller end towards said magazine and a spring normally holding said funnel clear of the filling side of the magazine, the articles moving on the conveyor being caused to enter the wider end of the funnel, the spring fingers of the funnel being arranged to give sufficient resistance to the passage of the articles therethrough to enable the resistance of the spring which holds the mouthpiece away from the magazine to be overcome to allow the articles to enter the lowermost packet in the magazine.

4. In a machine for wrapping and packing cigarettes or other small articles and in combination means for moving bunches of articles in succession, means for feeding a strip of wrapping material continuously across the path of the moving bunches of articles so that the latter make contact therewith, means for automatically severing a portion of said strip without interfering with the continuous feed of same, means for wrapping the severed portion around the articles without affecting the motion of the articles, a magazine adapted to receive a series of superposed packets with their open mouths arranged towards the wrapped articles moving on the conveyor

and an oscillating mouthpiece which receives the wrapped articles to be packed, operated by the movement of said articles to insert same in the lowermost packet in the magazine automatically.

5. In a machine for wrapping and packing cigarettes or other articles and in combination, a conveyor for moving the articles to be wrapped, a set of rotating rollers for continuously drawing wrapping material across the path of the articles moving on the conveyor so that the articles makes contact therewith, a rapid action knife for automatically severing a portion of said wrapping material without interfering with the continuous feed of same and folder plates arranged on each side of the conveyor between which the severed portion of wrapping material is carried by the articles moving on the conveyor to wrap said severed portion around the articles without affecting the motion of the articles, a magazine adapted to receive a series of superposed packets with their open mouths arranged towards the wrapped articles moving on the conveyor and an oscillating mouthpiece which receives the wrapped articles to be packed, operated by the movement of said articles to insert same in the lowermost packet in the magazine automatically.

In testimony whereof I have signed my name to this specification.

WALTER EVERETT MOLINS.
